JOHN THOMAS PILKINGTON, OF ENDERBY, BRITISH COLUMBIA, CANADA, ASSIGNOR
OF ONE-HALF TO STEPHEN LELLMAN, OF ENDERBY, CANADA.

CLOTHES-REEL.

1,119,633.

Specification of Letters Patent.

Patented Dec. 1, 1914.

Application filed June 13, 1913. Serial No. 773,465.

To all whom it may concern:

Be it known that I, JOHN T. PILKINGTON, a subject of the King of Great Britain, and a resident of Enderby, in the Province of 5 British Columbia and Dominion of Canada, have invented a new and Improved Clothes-Reel, of which the following is a full, clear, and exact description.

My invention relates to clothes reels having 10 a plurality of arms carrying separate clothes means.

A design of my invention is to provide a reel in which the several arms may be revolved separately or in unison; in which the 15 respective arms may be turned to bring them into vertical alinement whereby the reel may be run through a doorway or be conveniently placed on a veranda or in compact form adjacent to a building.

20 It is a further design of my invention to provide novel means for elevating the respective arms on the main post or standard.

It is also a design of my invention to improve in various particulars devices of the 25 general character indicated, to the end that efficiency in operation may be promoted as well as economy in manufacture and simplicity of adjustment and control.

The distinguishing features of my invention 30 and the improved structural elements characterizing the practical embodiment which is illustrated as an example will be more particularly explained in the specific description following.

35 Figure 1 is a side elevation of a clothes reel embodying my invention, dotted lines indicating a raised position of the arms; Fig. 2 is a plan view; Fig. 3 is a partial vertical section; Fig. 4 is a fragmentary 40 vertical section on a larger scale, parts being broken out; Fig. 5 is a sectional view on the line 5—5 of Fig. 4; Fig. 6 is a fragmentary perspective view of one of the sliding members to which the arms are secured; Figs. 7—8 and 9 are details to be 45 hereinafter referred to; Figs. 10, 11, 12 illustrate a modification; Fig. 13 is a fragmentary detail, in plan view of a modified arrangement of guide pulleys; and Fig. 14 50 is a side elevation of the parts shown in Fig. 13.

In constructing a clothes reel to embody

my invention in accordance with the illustrated example, a base 10 is provided on which the main post or standard 11 is supported, the base desirably being formed of radially extending arms secured to the post by brackets 12 and bolts 12^a.

A series of endless clothes lines 13, 13^a, 13^b, here illustrated as three in number, are 60 carried by radial arms 14, 15, 16, the arms for each of the clothes lines being arranged in pairs, the arms of each pair being diametrically opposite. The arms are secured to vertically sliding supports 17, 18, 19 fitted in vertical series on the main post 11. In order to elevate the clothes lines, a telescoping post section 20 is sleeved on the main post 11, and is adapted to be raised and lowered by a lift bar 21 fitted within the 70 post 11 and having guided movement by suitable guides such as elements 24. The lift bar is actuated by a rope 22 which is wound on the reel 23. The upper end of the telescoping post section 20 has a cap 25 preferably formed with a central bearing 26 against which a bearing ball 27 on the lift bar 21 has a bearing when the elevating slide 21 is raised by the rope 22. The result is that the cap will be raised by the said lift 80 bar and will carry upward the post section 20. In order that the upward movement of the telescoping post section 20 will successively raise the arms 14, 15, etc., and their respective clothes lines, each slide support 85 17, 18, 19, is provided with spaced collars 28, 29, 30, there being an upper and a lower collar on each slide, one of which is adapted to be engaged by collars 31, 32, 33 on the telescoping section 20. Thus the uppermost 90 collar 31 on the telescoping sections will engage the lower collar 28 on the upper slide 17, thereby raising the uppermost arms 14 and their clothes line 13. A continued movement of the telescoping section will cause the 95 next lower collar 32 thereon to engage the upper collar 29 on the succeeding slide 18 and carry the arms 15 of the latter and their clothes line 13^a upwardly. Next, the lowermost collar 33 on the telescoping section will 100 engage the upper collar 30 on the sleeve 19 and thereby raise the third set of arms 16 and their clothes line 13^b. With the several arms in the raised position, it will be obvious

that all will be supported on the ball bearing 27 of the slide 21, and also that the telescoping section 20 may be revolved on said bearing. In order that the several sets of 5 arms may revolve in unison with the revolving of the telescoping section, I provide for an interlocked engagement between the several slides 17, 18, 19 and the said telescoping section, to which end the collar on each slide 10 that is engaged by the collar on the telescope section is formed with corrugations indicated at 29^a in Fig. 6, and similar corrugations 31^a (Fig. 7) are produced on the opposed edges of the collars on the said telescoping section or equivalent means provided to effect an interlocked engagement 15 between the respective collars. The collars 31, 32, 33 may be secured in any suitable manner as by producing a hole 31^b therein 20 to receive a fastening pin to be passed into the section 20. It is possible also to raise any slide 17, 18, or 19 so as to disengage it from the telescoping section whereby any individual slide and each set of arms and the 25 clothes line may be revolved independently of the others, the result being that all the sets of arms may be disposed in cruciform as indicated in Fig. 2, or be so disposed as to all point in vertical alinement to present 30 the minimum total width in which adjustment the reel is adapted to be passed through a door into the house, or be placed close against the house as on a porch for instance. If it is not desired to utilize the locking 35 function of collar 31, the latter may be secured with its uncorrugated side uppermost.

For the moving of the reel and to bring the base into compact form to correspond with the folded position of the arms, the 40 base members 10 have their outer ends 10^a hinged as at 10^b so that the outer portions may be folded into parallelism as indicated in dotted lines, Fig. 2. Running rollers or casters 10^c may be provided on the outer 45 ends of the folding sections as indicated in Fig. 1.

The respective clothes lines are endless and supported on pulleys 34 which are mounted on the outer ends of their respective pairs of reel arms. The pulleys are adjustable to vary the distance between the respective pairs; the pulleys are held by keepers 35 and pins 36 which may be removed to adjust the pulleys, there being provided radial series of holes 37 in the arms 14, 15, etc. (See Fig. 8.)

In order to sustain the respective arms 14, 15, etc., against sagging under the weight of the clothes, the brace arms 38 are provided, 60 preferably in U-shape form as shown in Fig. 9, the U bend of the braces being rockable in eyes 39 of the respective arms. The inner ends of the braces are receivable in any convenient member as 40 on the slides 17, 18, etc., (see Fig. 6), the inner ends being

passed through said members and receiving the cotter pins 43 whereby the braces may be detached at their inner ends and permit the arms 14, 15, etc., to fold either upwardly or downwardly into approximate parallelism 70 with the main post. The braces 38 are surrounded near their lower ends by spiral springs 41 which serve to yieldingly sustain the arms and clothes line, the springs bearing at their inner ends against the members 40 of the slides, and at their outer ends against adjusting nuts 42 to vary their tension. 75

The slides 17, 18, 19 in the example shown consist of sections 44 (Fig. 6). The adjacent sides of each section are in the form of webs 45 which are integral with the collars 28, 29, etc., the arms 14, 15 etc., being secured as by pivot pins 46 or equivalent to the respective sections 44. In the illustrated 80 example also (see Fig. 4), the rope 22 from the reel 23 is shown as running into the interior of the fixed post 11 through a hole 11^a therein around a lower guide sheave 47 thence to an upper sheave 48 on said post, then downward and around a sheave 49 in the fork 21^a on the slide 21, and then to any suitable fixture 50 within the post. By the described arrangement, it will be seen that the rope has running engagement with the 85 sheave 49 on the slide 21. 90

Any suitable means may be provided for turning the reel 23. I have shown devices for giving a ratchet movement to the reel; thus a crank handle 23^a on the reel carries a pawl 51 which engages a ratchet 52, there being a second pawl or holding dog 51^a also in engagement with the ratchet. A pull wire 51^b may connect with pawl 51 and with a lever 51^c fulcrumed on crank handle 23^a. The reel may be removed if desired by loosening the bolt 53 on the bearing plates 54 that receive the journals 23^b of the reel. 100 105

Referring particularly to Fig. 1, it will be apparent that by reason of the spring 110 pressed brace arms 38, the tension of the springs may be such, and in practice will be such as to maintain the arms 14, 15, etc., at a slight angle above the horizontal, so as to dispose the pulleys at an inclination to 115 the horizontal, to better enable the line with the clothes directly pinned thereon to pass around the pulley without the line leaving the said pulleys. The arms are swung downwardly under the weight of the clothes, 120 and will finally approach or reach the horizontal position so that the opposite arms of each slide will be diametrically opposite or approximately so. Since as the arms move downwardly from a position at angles to 125 each other toward a position in line with each other, the opposite pulleys 34 will be at an increasing distance from each other, the result being that the line will be tightened and maintained on the pulleys and prevented 130

from leaving the pulleys. The arms 14, etc., constitute frames for supporting the line pulleys, and when arms are referred to, it is understood that any equivalent frame is meant.

5 In the form shown in Figs. 10 to 14, a series of frames 55, 56, 57 corresponding with those previously described are each provided with clothes lines 58 supported on pulleys 59 in the same manner as in the first-
10 construction. The arms are carried by tubular slides 61, 62, 63 mounted to revolve on a post 64 which is in practice supported in upper and lower brackets 65, 66, secured to the side or end of the house, the post extending substantially the height of the house or above the floors for which the several lines are intended. The arms are provided with spring pressed braces 38^a, similar to the
15 braces 38. The slides 61, 62, 63 are successively larger in diameter and designed to telescope when lowered. In order to raise and lower the several frames, a rope 67 is provided, one end of which is connected with a reel 68 from which the rope passes to a sheave 69 at the top of the building, and over a second sheave 70 on the upper bracket 65, to a connection with a loose collar 71 on the highest slide 61 beneath a flange 72
20 at the top of said slide. At the lower end of slide 61, a flange 73 is provided, adapted to contact with an inwardly projecting flange 74 on the upper end of the next lower slide 62, so that after the uppermost slide has
25 moved a given distance, it will engage and carry upward the second slide 62. Similarly, a flange 75 on the slide 62 will engage a flange 76 on the slide 63 and raise the latter. The several slides and their frames
30 may turn independently on the post 64, but in order to lock the frames in crossed form as in Fig. 11, one end of each frame carries a pivoted latch 77, one end being in hooked form, the opposite end being connected with
35 a retractile spring 78. The arrangement is such that the arms may be turned to cause the latch at the end thereof to engage a latch post 79, semi-circular in cross section, there being one of such latch posts at each
40 side of the central post in position to be engaged by the latches, the post 79 being secured by upper and lower brackets 80. The pivot pins 81 of the pulleys 59 may pass through the arms 55 at the ends and through
45 keepers 82 secured to said arms. I prefer to employ additional guard pulleys 83 as in Figs. 13 and 14, for each stretch of the ropes, said pulleys being carried on shafts 84 having bearings 85 on the keepers 82, the guard
50 pulleys thus turning on axes approximately perpendicular to the axes of the main pulleys 59. The guard pulleys 83, it will be observed, are above the clothes line, that is, the guard pulleys adjacent to a main pulley
55 are above the plane of the said main pulley.

Thus, while the guard pulleys serve to retain the clothes line from slipping from the main pulley as the arms sag downwardly under the weight of the clothes, the guard pulleys will not interfere with the endless line and the clothes directly pinned on the line from passing around the main pulleys.

Having thus described my invention, I claim as new and desire to secure by Letters Patent:

1. In a clothes drier, a support, a series of arms pivotally connected with the support at opposite sides to have a vertical pivotal movement, means on the outer ends of the arms for supporting a clothes line, and yielding braces extending from the arms to the support permitting the arms to yield under the weight of the clothes, the braces being adapted to normally sustain the arms at an angle above the horizontal and permit them to drop downwardly to increase the distance between the opposite supporting means for the clothes line.

2. In a clothes drier, a support, a series of arms pivotally mounted at opposite sides thereof to have a vertical pivotal movement, means on the outer ends of the arms for supporting a clothes line, and spring pressed braces pivotally connecting at their outer ends with the arms and yieldingly connecting with the support.

3. In a clothes reel, a post, a slide vertically movable on the post, arms extending in opposite directions from the slide and pivotally connected with the latter, braces pivotally connected at their outer ends with the arms and slidably at their inner ends in the slides, and springs on the braces normally tending to force the same outward, tending to raise the arms.

4. A reel comprising a post, a frame mounted to turn on the post and to slide vertically thereon, pulleys on said frame for carrying a clothes line, a latch post at each side of the reel, and latches on the frame for engaging said latch post.

5. A clothes drier including a frame, pulleys thereon to receive a clothes line, and guard pulleys adjacent to the first mentioned pulleys to prevent displacement of the clothes line, said guard pulleys turning on axes approximately perpendicular to the axes of the first pulleys and located above the plane of the main pulleys.

6. In a clothes drier, a support, arms on the support pivotally supported for movement in the vertical plane, means on the arms for supporting a clothes line, and yielding means adapted to normally sustain the arms at an upward inclination, said means being yieldable to the added weight of clothes on the line to permit the arms to approach a horizontal position.

7. A clothes drier including a frame, pulleys, and movable elements supporting the

pulleys at an inclination to permit the pulleys to automatically adjust themselves to any sag in the line due to the weight of the clothes, thereby allowing of the line with
5 the clothes directly pinned thereon passing freely around the said pulleys without the line being displaced.

In testimony whereof I have signed my name to this specification in the presence of two subscribing witnesses.

JOHN THOMAS PILKINGTON.
